[57] **ABSTRACT**

A copying device in which the original is scanned by a radiation source, and the radiation reflected from the original is projected onto a plurality of radiation sensitive members electrically connected to corresponding conducting elements. The conducting elements transmit current to an electrically conducting copy paper which is sensitive to current and/or heat to form images on the copy paper. The elements conduct a varying current in proportion to the radiation impinging on the radiation sensitive members for producing a copy locally or remotely of the original on the current and/or heat sensitive copy paper.

**COPYING DEVICE INCLUDING RADIATION
SENSITIVE MEMBERS ELECTRICALLY
RESPONSIVE TO THE REFLECTED IMAGE**

BACKGROUND OF THE INVENTION

1. Field of the Invention

This invention relates generally to copying devices, and more specifically to a copying device in which a copy of an irradiated original is locally or remotely formed on an electrical current and/or heat sensitive copy paper.

2. Description of the Prior Art

It is well known in the art to provide facsimile devices for transmitting and receiving images. For facsimile reception, a stylus is moved back and forth across the surface of a copy paper in slight pressure contact therewith and transmits electrical pulses to the paper in accordance with the image being transmitted. The electrical impulses generate heat in the particular areas in which they contact the copy paper to form images on the copy paper. Although such facsimile devices are satisfactory for the transmission and reception of images, the concepts involved therein are not adaptable to a high speed copying device in which an original is fed into the machine and a copy simultaneously removed therefrom locally or remotely. Such facsimile devices have the disadvantage of being slow since the stylus must move back and forth across the surface of the paper.

SUMMARY OF THE INVENTION

This invention includes within its scope copying devices in which the original is scanned by a radiation source, and the radiation from the original is projected onto a plurality of radiation sensitive members electrically connected to corresponding electrical conducting elements. The conducting elements transmit current to an electrically conducting copy paper which is sensitive to an electrical current and/or heat in proportion to the radiation impinging on the radiation sensitive members. The copy paper is subjected to the current in a varying dot pattern conforming to the radiation to produce a copy of the original. In a specific embodiment of the invention, the original is scanned on a line-by-line basis, and the conducting elements are located in spaced, parallel alignment with a copy paper support platen to form a passageway therebetween. The heat and/or electrical current sensitive copy paper is transported through the passageway and into engagement with the conducting elements to complete an electrical circuit connected to an alternating potential. Completion of the electrical circuit by the paper results in a current flow through the conducting elements and paper which is dependent upon the radiation received from the original by the radiation sensitive members. The current flow through the conducting elements and paper causes a change in appearance, such as a color change, to take place in the heat and/or electrical current sensitive copy paper to form a copy of the original.

It is therefore an object of the present invention to provide a copying device in which the original is irradiated and a copy formed locally or remotely on an electrical current and/or heat sensitive copy paper by a plurality of radiation sensitive elements responsive to radiation from the original.

Another object of the invention is to provide a copying device that is of simple design and construction, thoroughly reliable and efficient in operation, and economical to manufacture.

5 Another object of the invention is to provide a copying device capable of producing half-tone copies of an original.

The invention and its objects and advantages will become apparent in the detailed description of the 10 preferred embodiment presented below.

BRIEF DESCRIPTION OF THE DRAWINGS

In the detailed description of a preferred embodiment of the invention presented below, reference is 15 made to the accompanying drawings, in which:

FIG. 1 is a perspective view partly in section of one embodiment of the copying device of this invention;

FIG. 2 is a schematic view of the copying device of 20 FIG. 1 showing the electrical circuit for producing a positive copy of the original;

FIG. 3 is a schematic view similar to FIG. 2 showing the electrical circuit for producing a negative copy of the original;

25 FIG. 4 is a schematic view similar to FIG. 2 showing an electrical circuit for producing a half-tone copy of the original;

FIG. 5 is a segmental view in perspective of the radiation sensing means of the copying device;

30 FIG. 6 is an enlarged segmental view of a portion of the radiation sensing means of FIG. 5;

FIG. 7 is a side elevational view in section of another embodiment of this invention; and

35 FIG. 8 is a section view taken along line 8—8 of FIG. 7 and showing a portion of the radiation sensing means broken away.

**DESCRIPTION OF THE PREFERRED
EMBODIMENTS**

40 Because copying devices are well known, the present description will be directed in particular to elements forming part of, or cooperating more directly with, the present invention, copying device elements not specifically shown or described herein being understood to be selectable from those known in the art.

One embodiment of the copying device 10 of this invention comprises a housing having side walls 12, only one of which is shown in FIG. 1, for rotatably supporting the ends of opposed pressure transport rollers 14

50 for transporting an original 16 across an exposure slit 18 formed in the top wall 20 of the device 10. The front and rear walls 22, 24 respectively of the device 10 further support a reflector unit 26 to which a radiation means such as lamp bank 28 is secured for irradiating or exposing the original 16 as it is transported across exposure slit 18. The original 16 is preferably fed across exposure slit 18 with the information on the original facing the radiation source 28. The radiation

55 reflected from each line of information on the original varies by virtue of the difference in density of the line of information, the dark or black type or characters being not as reflective as the white background. The varying radiation is focused by an objective lens 30 mounted in a plate 32 supported by the device 10 onto a plurality of radiation sensitive members such as photocells 34, as best seen in FIGS. 4 and 5, for

producing a varying current flow. The photocells 34 are supported by an insulator bracket 36 secured to device 10 by leaf springs 38 in spaced, parallel relationship to exposure slit 18. Each of the radiation sensitive members 34 is electrically connected to a member such as a needle 40 mounted in bracket 36 in the form of a thin wire or a ribbon of metal preferably made of a composition customarily employed for resistance heating units operating at high temperature. Although needles 40 are mounted in close proximity to photocells 34, since the only connection therebetween is electrical, they could be separated, with the photocells and related irradiating apparatus at one location, and the needles and associated copy paper holding apparatus at a location remote therefrom. Directly below the needles 40 and spaced therefrom a distance slightly less than the thickness of a copy paper 42 is a support platen 44 as best seen in FIG. 1. The needles 40 are preferably resiliently mounted to allow copy paper 42 to be freely transported between the needles 40 and platen 44 with opposite sides of the paper in engagement therewith. The copy paper 42 may be any suitable paper such as a gelatin coated white paper soaked with a salt water solution to make it electrically conductive, and of the type which changes appearance, such as a color change, when subjected to current flow and/or heat. The copy paper 42 is transported by any suitable opposed rollers 46 and guides 48 through an entry slit 50 in the rear wall 24 of the device 10. The device may be provided with a tray 52 adjacent the entry slit 50 for preferably holding an electrolyte solution through which the copying paper 42 may be guided by any suitable guiding means, not shown, prior to its transport through the copying device 10 for coating or impregnating the paper with an electrically conducting solution such as an electrolyte. Instead of applying the electrolyte solution to the paper, the paper may be provided with a solid electrolyte coated thereon with the gelatin. Also, instead of guiding the copy paper through an electrolyte solution, the electrolyte may be provided in a capsule secured to the paper, the electrolyte contained therein being spread on the paper when the capsule is crushed upon passage through a pair of opposed rollers or the like.

Power is connected to the radiation sensitive members 40 through a bus bar 54 electrically connected to members 40 and secured to bracket 36. As indicated heretofore, bracket 36 is supported by leaf springs 38 which are secured to bracket 36 through insulator plates 56. As noted in the electrical wiring diagram shown in FIG. 2, a potential such as a 115 volt 60 hz. alternating current source is connected via the bus bar 54 to radiation sensitive members 34, and the current output thereof connected to needles 40. The support platen 44 is preferably connected to ground potential. When the electrically conducting copy paper 42 is transported through copying device 10, the paper completes an electrical circuit between needles 40 and platen 44. Since the radiation sensitive members 34 conduct current modulated in proportion to the radiation to which they are subjected, a dark image on original 16 will not reflect too much radiation causing the corresponding radiation sensitive member 34 to conduct very little current, if any, with the result that a change in appearance in the copy paper 42 does not occur.

On the other hand, a light portion of the original 16 will reflect considerable radiation onto a corresponding radiation sensitive member 34 causing it to conduct sufficiently to cause a change in appearance in the portion of the copy paper 42 with which it is in contact. One theory is that the change in appearance in the copy paper is due to the heat generated in the paper due to its inherent resistance rather than to the heat generated in the needle. In any event, the needles 40 will form an image line in the paper 42 that is a copy of the image line on the original 16. Whether a negative or positive copy is obtained depends on how an AC amplifier and resistor circuit 58 are connected into the circuit. With the circuit in FIG. 2, a positive copy is obtained whereas with the circuit of FIG. 3, a negative copy is obtained. The transport rollers 14, 46 for the original and copy paper respectively are drivingly connected together by belts 60 as seen in FIG. 2, and are driven by any suitable motor 62 so that the original and copy paper are transported in proper synchronization and in opposite directions. Any known switch, such as switch 59 shown in FIG. 2, may be provided to connect the radiation source 28 and transport motor 62 to a power source, and to disconnect them following completion of a copying cycle. Switch 59 may preferably remain in a normally open position and be closed upon movement of one of the rollers 14 when an original 16 is inserted into the nip of the rollers and transported therethrough. When the original 16 is transported all the way through the rollers 14, switch 59 will automatically open upon return of the rollers 14 into pressure engagement, disconnecting the power to the radiation source 28 and transport motor 62.

The bracket 36 supporting the radiation sensitive photocells 34 and needles 40 may be vibrated preferably at twice the power frequency or 120 hertz by any suitable means such as a solenoid 64 as seen in FIGS. 2 and 5 in a direction transverse to the paper travel a distance substantially equal to the pitch of the needles 40 (distance between two successive needles) so that the needles will cover the entire paper surface in the shortest possible time. Naturally, the greater the number of needles 40 and photocells 34 used, the faster the paper surface can be covered and a copy produced of the original. By intermittently applying the power to photocells 34 and needles 40, a half-tone copy can be produced. This may be accomplished as seen in FIG. 4 by rectifying the AC input by any suitable rectifier 61, and intermittently applying the output of rectifier 61 to the photocells and needles through any suitable make-and-break circuit 63 which operates at a frequency that is proportional to the AC voltage. When the voltage is low, which occurs when the needles are at each end of their travel, the frequency at which the power is broken is low. When the needle speed is greatest, the frequency at which the power is broken is the highest. This is necessary to provide a uniform spatial frequency of the dot pattern as is customary in normal half-tone production. By adjusting the amplitude of the bracket 36 so that it is equal to the pitch of the needles 40, and by vibrating the bracket 36 in resonance with the alternating current potential source such that a needle 40 travels a distance equal to the pitch of the needles during each half cycle of the power source, it has been noted that the voltage required is proportional to the

needle speed. Accordingly, as the number of needles 40 used is increased, the needle speed that is necessary is decreased, and the voltage required to operate the copying device is decreased.

In the embodiment of the invention shown schematically in FIGS. 7 and 8, parts similar to parts shown in FIGS. 1-6 will be denoted by the same numerals primed. In this embodiment, the entire original 16' is irradiated by a radiation source 28', and the reflected image or radiation focused by any suitable lens system 30' onto a plurality of radiation sensitive photocells 34', only a portion of which are shown in FIG. 8, arranged to receive all of the radiation from the original. As described in the embodiment of the invention shown in FIGS. 1-6, the photocells 34' are connected to corresponding needles 40'. A copy paper 42' is manually moved through an entry door 65 and placed on a pivotally mounted support platen 67 which is moved to a latched copying position as shown in full lines, in which the copy paper is held in engagement with the needles 40'. To assure complete coverage of the copy paper 42' by needles 40', in addition to vibrating means 64' for moving the bracket 36' transversely of the paper 42' through a distance equal to the transverse distance between the needles 40', any suitable transport means 68 such as a solenoid must be provided (See FIG. 7) to move the bracket 36' longitudinally of the paper through the longitudinal distance between the needles 40'. Following such transverse and longitudinal travel for a predetermined time to make a copy, a switch, not shown, is actuated by any suitable means to disconnect the power to the device. The bracket 36' is returned to its original normal position by springs 70.

The invention has been described in detail with particular reference to a preferred embodiment thereof, but it will be understood that variations and modifications can be effected within the spirit and scope of the invention as described hereinabove.

I claim:

1. In copying apparatus for reproducing a copy of an original on a copy medium and including an irradiating station and means for irradiating an original bearing an image which is positioned at the irradiating station to produce a radiation image corresponding to the original, the combination comprising:

- a. radiation sensing means located with respect to said irradiating station to receive the radiation image from the original for producing an electrical image signal corresponding to a received radiation signal;
- b. copying station means for receiving a copy medium;
- c. means adjacent said copying station for transmitting the electrical image signal to the copy medium and including a plurality of electrically conductive members;
- d. support means for supporting the plurality of electrically conductive members which are spaced a first distance apart in a first dimension with respect to the copy medium and which are spaced a second distance apart in a second dimension with respect to the copy medium;
- e. first vibrating means for vibrating said support means in said first dimension a distance substantially equal to said first distance; and

f. second vibrating means operating in timed relation to said first vibrating means for vibrating said support means in said second dimension a distance substantially equal to said second distance.

5 2. The apparatus of claim 1 wherein said radiation sensing means comprises a plurality of photoreceptors each adapted to provide a signal, the totality of said photoreceptor signals comprising said electrical image signal, and wherein said plurality of electrically conductive members comprise discharge means that are electrically connected to said plurality of photoreceptors for receiving the varying signals therefrom.

10 3. The apparatus of claim 1 including:

- a. power means for supplying an AC voltage of a predetermined frequency;
- b. rectifier means connected to said power means for rectifying said AC voltage;
- c. conductor means for supplying said rectified AC voltage to said radiation sensing means; and
- d. interruptor means connected between said rectifier means and said conductor means for interrupting the rectified AC voltage supplied to said sensing means at a frequency proportional to the voltage of said rectified voltage.

15 4. The apparatus of claim 3 wherein said first said vibrating means vibrates said support means at a frequency which is resonant with said frequency of said AC voltage.

20 5. The apparatus of claim 3 wherein said first vibrating means vibrates said support means at a frequency twice said frequency of said AC voltage.

25 30 6. In copying apparatus for reproducing a copy of an original on a copy medium and having an irradiating station whereat radiation is directed onto an original for providing a radiation image in accordance with the original;

35 40 radiation sensing means for producing an electrical image signal proportional to the radiation sensed; means for directing the radiation image from the original onto said radiation sensing means to produce said image signal in response to the radiation image; and

45 first support means for supporting a copy medium with respect to said radiation sensing means such that the image signal from said radiation sensing means is electrically transmitted to the copy medium to form a copy corresponding to the original, the improvement in said radiation sensing means comprising:

- a. a plurality of electrically conductive members;
- b. second support means for supporting said plurality of electrically conductive members which are spaced a first distance apart in a first dimension with respect to the copy medium and which are spaced a second distance apart in a second dimension with respect to the copy medium;
- c. first vibrating means for vibrating said second support means in said first dimension with respect to the copy medium a distance substantially equal to said first distance; and
- d. second vibrating means operating in timed relation to said first vibrating means for vibrating said support means in said second dimension a distance substantially equal to said second distance.

7. The apparatus of claim 6 wherein said radiation sensing means comprises a plurality of photoreceptors each providing a signal, the totality of said photoreceptor signals comprising said electrical signal image and wherein said plurality of electrically conductive members comprise discharge means that are electrically connected to said plurality of photoreceptors to receive the signals therefrom.

8. In copying apparatus for reproducing a copy of an original on a copy medium and having an irradiating station, and radiation means for irradiating an original bearing an original image and positioned at the irradiation station to produce a radiation image corresponding to the original image, said apparatus comprising:

- a. radiation sensing means disposed to receive the radiation image from the original for producing an electrical image signal corresponding to the radiation image received;
- b. power means for supplying an AC voltage of predetermined frequency to said radiation sensing means;
- c. copying station means for receiving a copy medium;
- d. means adjacent said copying station means for transmitting the electrical image signal to the copy medium to form thereon a copy of the original, said means for transmitting including a plurality of electrically conductive members;
- e. support means for supporting the plurality of electrically conductive members which are spaced a first distance apart in a first dimension with respect

to the copy medium, and which are spaced a second distance apart in a second dimension with respect to the copy medium;

- f. first vibrating means for vibrating said support means in said first dimension a distance substantially equal to said first distance and at a frequency which is an integral multiple of the predetermined frequency of said power means; and
- g. second vibrating means operating in timed relation to said first vibrating means for vibrating said support means in said second dimension a distance substantially equal to said second distance.

9. The apparatus of claim 8 wherein said radiation sensing means comprises a plurality of photoreceptors each providing a signal, the totality of said photoreceptor signals comprising said electrical image signal, and wherein said plurality of electrically conductive members comprise discharge means that are electrically connected to said plurality of photoreceptors for receiving the varying signals therefrom.

10. The apparatus of claim 8 wherein said first vibrating means vibrates said support means at a frequency which is twice the frequency of said predetermined frequency of said power means.

11. The apparatus of claim 1 wherein said second vibrating means vibrates said support means in said second dimension in synchronism with said first vibrating means.
